UNITED STATES PATENT OFFICE

165,877

RUBBING MACHINE

Steven E. Scace, Cicero, Ill., assignor to Speedway Manufacturing Company, a corporation of Illinois

Application May 24, 1951, Serial No. 15,298

Term of patent 14 years

(Cl. D9—2)

To all whom it may concern:

Be it known that I, Steven E. Scace, a citizen of the United States, residing in Cicero, county of Cook, and State of Illinois, have invented a new, original, and ornamental Design for a Rubbing Machine, of which the following is a specification, reference being had to the accompanying drawing, forming a part thereof, in which:

Figure 1 is a side elevational view of the rubbing machine; Figure 2, a top plan view of the same; and Figure 3, a front elevational view, showing my new design.

I claim:

The ornamental design for a rubbing machine, as shown.

STEVEN E. SCACE.
